UNITED STATES PATENT OFFICE.

CLEMENT C. CLAWSON, OF NEWARK, NEW JERSEY.

DESIGN FOR A CASE FOR COIN-RECEIVERS.

SPECIFICATION forming part of Design No. 24,345, dated May 28, 1895.

Application filed March 30, 1895. Serial No. 543,903. Term of patent 7 years.

To all whom it may concern:

Be it known that I, CLEMENT C. CLAWSON, a citizen of the United States, residing at Newark, in the county of Essex and State of New Jersey, have invented and produced a new and original Design for Cases for Coin-
5 Receivers; and I do hereby declare the following to be a full, clear, and exact description of the same, reference being had to the accompanying drawings, forming a part hereof.

In said drawings, Figure 1 is a perspective view of a case embodying the design; and Fig. 2 is a cross-section of the case, said section being taken on line *x* in said Fig. 1.

The leading features of my new and original design for cases for coin receivers are a frame *a* with its upper edges and corners rounded, as at *a'*. The base *b* of the case, on which said frame *a* is arranged, is provided with the rounded edges and corners *b'* and the ornamental rib or raised portion *b*² surrounding the lower portions of said frame *a*.

when the latter is in position on its base *b*. In the upper surface *a*³ of said frame *a* is an opening *a*³ bounded by three circular curves or arches *a*⁴ which meet to form the cusps *a*⁵, the complete opening forming a trefoil, resembling a three-leaved clover. Said top is also provided with a slit *a*⁶.

The essential feature of my new and original design for a case for coin receivers, therefore, is the arrangement of an opening in the form of a trefoil in the frame or cover *a* of the case, as shown.

Having thus described my invention, what I claim is—

The design for a case for coin receivers, substantially as herein shown and described.

In testimony that I claim the invention set forth above I have hereunto set my hand this 28th day of March, 1895.

CLEMENT C. CLAWSON.
